UNITED STATES PATENT OFFICE.

GEORGE J. B. RODWELL, OF TORONTO, ONTARIO, CANADA, ASSIGNOR OF
ONE-HALF TO WILLIAM DICKS, OF SAME PLACE.

HAND-STAMP.

SPECIFICATION forming part of Letters Patent No. 265,872, dated October 10, 1882.

Application filed November 15, 1881. (No model.)

To all whom it may concern:

Be it known that I, GEORGE JAMES BEL-LAMY RODWELL, of the city of Toronto, in the county of York, in the Province of Ontario, Canada, have invented certain new and useful Improvements in Hand-Stamp, of which the following is a specification.

The object of the invention is to produce a neat hand-stamp which can be conveniently carried in the pocket, will always be ready for use, and can be handled without fear of soiling the fingers; and it consists essentially of two oblong cases, the bottom of one being provided with a felt pad placed over a piece of sponge or other porous material containing the liquid ink with which the pad is to be saturated, this first case being arranged to receive within it a similarly-shaped case having on its bottom the type, and also arranged, if necessary, to form an ink-reservoir for holding a surplus supply of ink.

Figure 1 is a sectional-elevation, showing the interior arrangement of my improved hand-stamp. Fig. 2 is an outside view.

It will be noticed in the drawings that the bottom of the outer casing, A, has formed on it a suitable chamber to receive a sponge, a, or other porous material suitable to contain a liquid ink, with which it is saturated.

b is a pad, made of felt or other suitable material, and made to fit tightly the interior of the casing A, covering the sponge a, as indicated.

B is an inner casing, made to fit, as indicated, within the outer casing, A. The inner casing, B, is made to form a liquid-tight compartment having but one aperture, which is hermetically sealed by a proper stopper, C. This chamber is intended to contain a surplus supply of ink in order to have at all times a ready means of resaturating the sponge a.

I may here mention that by having the ink-

pad placed at the bottom of the casing A the ink cannot be affected by the light, while the fact that the inner casing, B, fits tightly the outer casing, A, insures that when the two are placed together all dust will be kept from the pad and type.

In a recess made in the bottom of the inner casing, B, I fit the type E, either cut on the face of a rubber strip or otherwise, as may be desired by the manufacturer, provided that it is so fitted that it can be removed easily and replaced by type differently arranged.

C is a stopper screwed into the aperture through which the ink is supplied into the casing B. This stopper may have a brush, D, extending from it, as shown, which brush may be used for the purpose of applying the ink to the pad b or sponge a, as the case may be.

In order to prevent the type E coming in contact with the pad b when it is not desired to have them so applied, I provide springs F, preferably attached to the flange or the casing B, as shown in Fig. 2, so that they will come in contact with the end of the casing A, and will not till compressed allow the type to come in contact with the pad.

What I claim as my invention is—

In a hand-stamp, the combination, with an outer case, A, provided with an inking-pad, b, of the hollow removable inner case, B, carrying type, and provided with a stopper, C, and a brush, D, and the springs F, secured to the case B, and adapted to rest upon the edge of the case A, substantially as and for the purpose specified.

G. J. B. RODWELL.
